UNITED STATES PATENT OFFICE

CHARLES F. MEYER, OF BALTIMORE, MARYLAND.

DESIGN FOR A WINE-COOLER.

SPECIFICATION forming part of Design No. 12,831, dated March 21, 1882.

Application filed December 24, 1881. Term of patent 14 years.

To all whom it may concern:

Be it known that I, CHARLES FERDINAND MEYER, a citizen of the United States, residing in the city of Baltimore, in the State of Maryland, have invented and produced a new and original Design for a Wine-Cooler, of which the following is a specification, reference being had to the accompanying drawings, forming part hereof.

10 Figure 1 is a front view of my newly designed wine-cooler when ready for use. Fig. 2 is a corresponding upright view. Fig. 3 represents the cooler with the top removed and the outer bell-shaped inclosure, these three 15 views being deemed necessary to fully illustrate my new design.

A is the cylindrical receptacle for the bottle of wine.

20 C is the bail or handle of the cooler, turning on swivels.

Fig. 1 shows a representation of the imperial arms of Russia, beneath which are the words

"Bell of Moscow;" and Fig. 2 shows the words "Bell of Moscow Champagne."

The ornamentation shown in the drawings 25 is partly struck up and partly engraved; but the whole may be struck up, or engine-turned, or effected by other means used for similar purposes.

The leading feature of my said design is the 30 peculiar bell shape of the complete device.

I claim—

1. The design for a wine-cooler herein shown and described, the same consisting of the bell-shaped device with the top B and bail C. 35

2. The design for a wine-cooler herein shown and described, the same consisting of the principal or bell-shaped part, the representation of the arms of Russia, top B, and the bail C.

CHARLES FERD. MEYER.

Witnesses:

FELIX R. SULLIVAN,
JAMES J. DUENBERGER.
